BERNARD MORGAN, OF NEWPORT, RHODE ISLAND.

HAND-TOOL.

1,050,746.

Specification of Letters Patent.

Patented Jan. 14, 1913.

Application filed February 26, 1912. Serial No. 679,857.

To all whom it may concern:

Be it known that I, BERNARD MORGAN, a subject of the King of Great Britain, and a resident of Newport, in the county of 5 Newport and State of Rhode Island, have invented a new and Improved Hand-Tool, of which the following is a full, clear, and exact description.

The object of the invention is to provide 10 a new and improved hand tool, which is simple and durable in construction, easily manipulated and designed for various uses by mechanics, plumbers, chauffeurs and other persons, to permit such persons to use 15 the tool as a clamp, or as a spreader and stretcher for coil springs, or as a valve lifter, etc.

For the purposes mentioned, use is made 20 of a screw rod, oppositely-disposed jaws, of which one is fixed on the screw rod and the other is movable on the screw rod in the direction of the length thereof, each of the 25 jaws being provided at one side of the screw rod with a fork and at the opposite side with a pin, and a nut screwing on the screw rod and moving with the movable jaw, the nut having peripheral teeth engaged by a reversible pawl held in a hand lever mounted to swing on the nut.

30 A practical embodiment of the invention is represented in the accompanying drawings forming a part of this specification, in which similar characters of reference indicate corresponding parts in all the views.

35 Figure 1 is a perspective view of the hand tool applied to a coil spring for stretching the same; Fig. 2 is an enlarged sectional plan view of the hand tool, the section being on the line 2-2 of Fig. 3; Fig. 3 is a sectional side elevation of part of the screw rod, movable jaw and the nut and hand lever; Fig. 4 is a perspective view of the hand tool applied for lifting the valve from an internal combustion engine; and Fig. 5 45 is a perspective view of the hand tool applied as a clamp.

On one end of the screw rod A is secured a jaw B operating in conjunction with a jaw C movable on the screw rod A, and arranged opposite the jaw B. The fixed jaw B and the movable jaw C are provided at one side of the screw rod A with oppositely-disposed forks B', C' and the said jaws are provided on the opposite side of the screw rod A with pins B², C² extending outwardly

and arranged opposite each other, as will be readily understood by reference to the drawings. The movable jaw C is provided with a forked hub C³ mounted to slide loosely on the screw rod A, and the members of the hub C³ are provided with inwardly-extending lugs C⁴, C⁵ engaging a longitudinal groove A' formed in the screw rod A so that the movable jaw C is held against turning on the screw rod A. Between the members of the hub C³ is arranged a nut D screwing in the arrow rod A, and on the said nut D is mounted to swing loosely the forked end E' of a hand lever E provided with a hollow handle E² adapted to be taken hold of by the operator for imparting a swinging motion to the lever E. The nut D is provided on its peripheral face with teeth D' adapted to be engaged by a reversible pawl F held in the inner end of the hollow handle E² of the lever E, and the said reversible pawl F is provided with a stem F' extending through a hollow handle E² and terminating at its outer end in an angular arm F² adapted to engage diametrically-disposed notches E³ arranged on the outer end of the hollow handle E². A spring G extends within the hollow handle E² and presses against the reversible pawl F so as to hold the same in engagement with adjacent teeth D' of the nut D and at the same time hold the arm F² in engagement with either of the notches E³, as plainly indicated in Fig. 2.

When the several parts are in position as shown in Fig. 2 and a swinging motion is given to the handle E² of the lever E in the direction of the arrow a' then the pawl F carries the nut D along and thus screws the same outward on the screw rod A thereby moving the movable jaw C in a like direction, that is, away from the fixed jaw B. When the lever E is swung backward in the inverse direction of the arrow a' then the pawl F glides over the teeth D' and hence the nut D and the movable jaw C remain at a standstill. When it is desired to move the movable jaw C toward the fixed jaw B then the operator pulls the arm F² outward to disengage the pawl F from the teeth D', and then gives a half turn to the arm F² so as to reverse the pawl F relative to the teeth D', and when the operator now releases the arm F² then the spring G moves the pawl F into engagement with the teeth D' but in a

reverse direction to the one previously occupied. When a swinging motion is now given to the lever E in the reverse direction of the arrow a' then a like turning motion is transmitted to the nut D to screw the same inward on the screw rod A thus moving the jaw C toward the fixed jaw B. When the lever E is swung in the direction of the arrow a' the pawl F glides over the teeth 10 D' and consequently the nut D and the jaw C remain at a standstill.

The tool described may be used for various purposes, for instance, as shown in Fig. 1, a spring H can be stretched by attaching the ends of the spring to the pins C², B² and then manipulating the lever E so as to move the jaw C outward away from the jaw B thus stretching the spring H. When the pawl F is reversed then the tool can be used 20 for clamping purposes (see Fig. 5) by placing the jaws B and C in engagement with the parts to be clamped and then manipulating the lever E so as to move the jaw C toward the fixed jaw B thus clamping the 25 parts together. The tool can also be used for lifting a valve off its seat, as indicated, for instance, in Fig. 4, it being understood that in this case the slotted jaws B', C' straddle the stems, and on imparting a 30 swinging motion to the lever E the movable jaw C is moved outward on the screw rod A, thus lifting the valve stem and consequently the valve off its seat. When it is desired to compress a spring, such spring may 35 be placed within the jaws B and C and the jaw C moved inward on the screw rod for the purpose mentioned.

In the foregoing it is only intended to give a few examples of the use of the tool, 40 as it is evident that the same can be used for many purposes.

Having thus described my invention, I claim as new and desire to secure by Letters Patent:

45 1. A hand tool, comprising a screw rod, a fixed jaw secured at one end on the said screw rod and extending at a right angle thereto, a movable jaw having at one end a forked hub mounted to slide on the said screw rod, 50 the said jaws being slotted, a nut screwing on the said screw rod and extending in the said fork of the said hub, the said nut being provided with peripheral teeth, and a hand lever mounted to swing loosely on the

said nut and provided with a reversible pawl 55 for engaging the teeth of the said nut.

2. A hand tool, comprising a screw rod provided with a groove extending lengthwise of the screw rod, a jaw fixed at one end on one end of the said screw rod and extending at a right angle thereto, the jaw being slotted, a movable jaw extending parallel to the said fixed jaw and slotted, the said movable jaw having a forked hub slidably engaging the said screw 65 rod groove, a nut screwing on the said screw rod and arranged between the members of the said forked hub, the said nut being provided on its periphery with teeth, a lever mounted to swing loosely on the said nut, 70 and a reversible pawl carried by the said lever and adapted to engage the said nut teeth.

3. A hand tool, comprising a screw rod provided with a groove extending lengthwise of the screw rod, a slotted jaw fixed at one end on one end of the said screw rod and extending at a right angle thereto, a movable jaw extending parallel to the said fixed slotted jaw and slotted at one side 75 opposite the jaw having a forked hub slidably engaging the said screw rod, lugs on the hub engaging the said screw rod groove, a nut screwing on the said screw rod and arranged between the members of the said 80 forked hub, the said nut being provided on its periphery with teeth, a forked hand lever mounted to swing loosely on the said nut and having a hollow handle provided at its outer end with diametrically-disposed 85 notches, a reversible pawl engaging the said nut teeth and provided with a stem extending loosely through the said hollow handle, the outer end of the said stem having an angular arm adapted to engage the said 90 notches in the handle, and a spring within the hollow handle and pressing the said pawl to hold the latter in engagement with the said nut teeth and to hold the arm of the said stem in engagement with either of the 95 said handle notches.

In testimony whereof I have signed my name to this specification in the presence of two subscribing witnesses.

BERNARD MORGAN.
